UNITED STATES PATENT OFFICE.

ALBERT BRUCKNER, OF ETNA, PENNSYLVANIA.

MOLD FOR ARTIFICIAL STONE.

1,186,275.

Specification of Letters Patent. Patented June 6, 1916.

Application filed July 28, 1915. Serial No. 42,297.

To all whom it may concern:

Be it known that I, ALBERT BRUCKNER, a citizen of the United States, residing at Etna, in the county of Allegheny and State 5 of Pennsylvania, have invented new and useful Improvements in Molds for Artificial Stone, of which the following is a specification.

My invention relates to molds for manufacturing artificial stone blocks, having double or parallel walls connected together by metal ties.

It is the object of this invention to provide an improved apparatus of the collapsible or knock-down type by which such blocks may be made cheaply and rapidly.

Referring to the accompanying drawings, Figure 1 is a plan view of a mold constructed in accordance with my invention 20 for making a corner block; Fig. 2, a vertical section on the line II—II, Fig. 1; Fig. 3, a side view of one of the sides of the core of the mold; Fig. 4, a perspective view of one of the spacers or separators for the sides 25 of the core; Fig. 5, a plan view of a mold for making straight blocks; Fig. 6, a section on the line VI—VI, Fig. 5; Fig. 7, a perspective view of a block made in the mold shown in Figs. 5 and 6; and Fig. 8, a section 30 of a block, the section corresponding to the line II—II, Fig. 1.

Referring first to Figs. 1 to 4, 1 and 2 represent the mold sides for shaping the outer surfaces of a corner block, and 3 and 35 4, the mold sides for shaping the inner faces of a corner block. The sides 1 and 2 are preferably secured together at right angles to each other and constitute the outer side member A of the mold; and the sides 3 and 40 4 are also preferably secured together at right angles to each other and constitute the inner side member B of the mold. The members A and B are arranged in parallel relation to each other, so as to form between 45 them the mold sides for the inner and outer faces of a corner block. The outer ends of the parallel members 1 and 3 extend into mortises 5 in the closure 6 of one end of the mold and the outer ends of the parallel 50 members 2 and 4 extend into mortises 7 in the closure 8 of the other end of the mold. The sides and ends of the mold may be held in the assembled position shown in various ways, but I have shown the braces 9 adjustably secured to the mold bottom 10 by

bolts 11 in the slots 12 in the braces, nuts 13 clamping the braces to the bottom 10. The inner faces of the members A and B are provided with beveled recesses 14 which provide the molded blocks with projecting 60 beveled portions 14^b. The end member 6 has the recess 15 midway between the sides 1 and 3, and the end member 8 has the recess 16 midway between the sides 2 and 4. 17 and 18 are two members arranged parallel 65 to the sides 1 and 2 and have their meeting ends secured together in any proper manner, as by the pin 19 extending through the hinge-lugs 20 (Fig. 3). The remaining ends of the members 17 and 18 extend into the 70 recesses 15 and 16 and rest against the outer walls thereof. 21 and 22 are two members similar to the members 17 and 18. They have their meeting ends secured together by the pin 23 and have their remaining ends 75 resting against the inner walls of the recesses. The members 17 and 18 support projections 24 which face toward the sides 1 and 2 in order to form recesses 25 in the molded blocks. The members 21 and 22 80 also carry projections 26 which face toward the sides 3 and 4 in order to form recesses 27 in the blocks. The members 17, 18, 21 and 22 are each divided longitudinally into upper sections a and lower sections b (Fig. 85 2). The sections a have open slots 28 on their upper edges to support the metal ties 29, and the sections b have open slots 30 in their lower edges to receive the metal ties 31, only one tie being shown, Fig. 2. The members 17, 18 are held in the spaced position shown by the spacers 32, each comprising a horizontal member 33 and a pair of members 34 depending therefrom. The members 33 and 34 are as wide as the space 90 between the parallel members 17, 21 and 18, 22. The members 34 extend down between the members 17, 21 and 18, 22 while the members 33 lie between the upper edges 95 of the members 17, 21 and 18, 22 and flush therewith. It is seen that my mold has two L-shaped mold spaces C and D, separated by a partition comprising the members 17, 18, 21, 22, 33 and 34. The metal ties have 100 their forked ends projecting into the mold spaces C and D. Cement is poured into the spaces C and D until the spaces are filled. It may be poured over the mold without care as to the partitions since the members 33 prevent any cement from running into 105 110 115

the space between the members 17, 21 and 18, 22. After the mold has been filled the cement is scraped off the top and the block of cement is allowed to set or harden. 5 When the block is hard enough to stand with its sides unsupported, the sides and ends of the mold are removed. Also the spacers 32 are withdrawn. Then the sections *a* and *b* are removed. It is seen that, by having 10 the ties near both edges of the block, the members 17, 18, 21 and 22 should be made in sections in order that they may be removed.

Referring now to Figs. 5, 6 and 7, I show 15 a mold for making a straight block. The parallel, straight sides 1^a and 3^a are seated in mortises 5^a in the ends 6^a of the molds. The ends 6^a have the recesses 15^a to receive the ends of the partition composed of the 20 straight parallel members 17^a and 21^a and the spacer 32^a, comprising the horizontal member 33^a and the vertical members 34^a. The members 17^a and 21^a are composed of 25 upper sections *a*¹ and *b*¹, provided with the projections 24^a and 26^a extending into the mold spaces C¹ and D¹ respectively. 29^a and 31^a represent metal ties constructed and arranged like the ties 29 and 31. I have shown the ends 6^a of indefinite length, so 30 that other blocks can be molded between them beyond the side 1^a. For the same purpose I have shown the sides 1^a and 3^a, which are interchangeable, with the lateral extensions 35, also shown on Fig. 1, in which the 35 recesses 14 and 14^a are made. The ends 6^a have mortises 5^a and recesses 15^a on both sides so that the mold may be extended end- 40 wise as well as sidewise, as shown at the right-hand side of Fig. 5. 10^a is the mold bottom.

In Fig. 7, I have shown the block made by the mold shown in Figs. 5 and 6. It comprises the members E and F which were cast

in the mold spaces C¹ and D¹, connected together by the ties 29^a and 31^a. 45

I claim:

1. In a mold, a pair of spaced mold sides, closures for bridging the space between the ends of the said mold sides, and a partition arranged parallel with the mold sides and 50 between the same and having its ends in engagement with the said closures, the said partition comprising spaced side members and a removable spacing member to hold the side members at a predetermined distance 55 apart, the said side members having at each edge open slots to receive ties bridging the said side members and having their ends in the spaces between the partition and the mold sides, and the said side members being divided longitudinally between the ties in the respective notches so as to form separable sections, whereby the said partition may be removed from an article molded in the spaces between the mold side and the said 60 partition.

2. In a mold for corner blocks, parallel L shaped members arranged to shape the opposing sides of a corner block, end closures bridging the spaces between the ends of the 70 L shaped members, an L shaped partition between the said L shaped members, the said partition comprising spaced L members having notches at both edges, adapted to hold ties, bridging the spaces between the side-members and having their ends in the spaces between the partition and the mold sides, each L-shaped member comprising portions detachably connected together at the angle thereof and divided longitudinally between 75 the ties in the notches at the respective edges of the side members. 80

Signed at Pittsburgh, Pa., this 27th day of July, A. D. 1915.

ALBERT BRUCKNER.
